[57] CLAIM

The ornamental design for a cable sleeve for absorbing electric noise, as shown and described.

DESCRIPTION

FIG. 1 is a front elevational view of a cable sleeve for absorbing electric noise showing my new design, the rear elevational view being a mirror image;

FIG. 2 is a bottom plan view thereof;

FIG. 3 is a right side elevational view thereof; the left side elevational view being a mirror image resulting from the interconnection of the two identical halves;

FIG. 4 is a right side elevational view thereof shown in the open condition;

FIG. 5 is a cross-sectional view thereof taken on line 5—5 of FIG. 4;

FIG. 6 is a cross-sectional view thereof taken along line 6—6 of FIG. 4;

FIG. 7 is a perspective thereof shown in the open condition;

FIG. 8 is a perspective view thereof;

FIG. 9 is a perspective view thereof shown in use with an electrical conductor. The conductor shown in broken lines is for illustrative purposes only and forms no part of the claimed design.
